UNITED STATES PATENT OFFICE.

HARRY G. AINSWORTH, OF KENTLAND, INDIANA.

DOOR-OPERATING MECHANISM.

Application filed May 12, 1922. Serial No. 560,291.

To all whom it may concern:

Be it known that I, HARRY G. AINSWORTH, a citizen of the United States, residing at Kentland, in the county of Newton and

5 State of Indiana, have invented certain new and useful Improvements in Door-Operating Mechanism, of which the following is a specification, reference being had to the accompanying drawings, and to the reference 10 characters marked thereon, which form a part of this specification.

This invention relates to door operating mechanism and more particularly to mechanism designed to open and close heavy 15 swinging doors, such as garage doors; the operating mechanism being actuated by a suitable power device.

The primary object of the present invention is to provide improved mechanical 20 means to accomplish the above operation. The invention consists in the devices and combination of devices herein illustrated and described, and more particularly pointed out in the appended claims.

25 With the above and other objects in view, I refer to the accompanying drawings, in which—

Fig. 1 is an inside view of a structure provided with a pair of hinged doors, to which 30 the mechanism embodying the present invention has been applied, part of the view being in section and taken upon the plane indicated by the dotted line 1—1 of Fig. 2.

Fig. 2 is a top or plan view, partially in 35 section, of said mechanism.

Fig. 3 is a side elevation of a detail of the mechanism, partly in section, to show the locking and unlocking lever.

Fig. 4 is a bottom plan view of the mechanism shown in Fig. 3.

Fig. 5 is a plan detail, partly in section, of a modification.

Fig. 6 is a detail of another modification.

In said drawings, A represents the frame 45 of a suitable garage or other structure, which is provided with a pair of doors, B, B, hinged at b, b; the doors having meeting edges indicated by the vertically disposed line a. C, C, are a pair of horizontally ar-

50 ranged, parallel beams or timbers, positioned in the structure A at a point above the upper edge c of the doors B, B, and at right angles to the position of the doors when closed, as indicated clearly in Figs. 1 and 2. No supports for these timbers or

beams C, C, are indicated in the drawings, as they may be a part of the building structure or they may be secured to the building A in any convenient or conventional manner.

55 Mounted upon these timbers C, C, by means of pedestals 1, or any other suitable means, is a housing 2, having suitable bearing for the vertically arranged, rotatable operating shaft 3. The shaft 3 may be rotated by any suitable operating mechanism mounted upon or contained within the housing 2, but that shown in the drawings is the mechanism illustrated and claimed in my copending application, Serial No. 466- 60 252, filed May 2nd, 1921, which is recommended as a satisfactory mechanism for operating the shaft 3.

65 Briefly, the mechanism illustrated comprises a worm gear 4, a worm 5, an electric motor 6, and suitable connections whereby power may be supplied to the motor, through circuit lines 7 and 8, suitable switches indicated at 9, and a belt connection 10 between the motor shaft 10^a and the worm shaft 11. For further details of the operation of this particular operating device, I refer to my said copending application.

70 On the lower end of the operating shaft 3 is a crank arm 12, pivotally connected at 13 to a movable block or plate D. Through an intermediate connecting link 14, the plate D has sliding engagement with and between the beams or timbers C, C, which latter form longitudinal guideways for said block or plate D. In the present instance, each of the timbers C is provided on its inside face with suitable groove or guideway 15, and the plate D is provided on its two side margins with laterally extending lugs 16; the lugs 16, 16 and guideways 15, 15, being complementally arranged so that the plate D may be held between said timbers and yet be moved longitudinally thereof.

75 It will be understood that upon the rotation of the shaft 3, the crank arm 12 will be rotated from one position, shown in dotted lines in Fig. 2, to the other position shown in dotted lines in said figure, with the result that the plate D will be moved toward or away from the doors B, B, as the case 80 85 may be.

85 Each door B, B, is provided with a pair of links 17, 18, pivotally joined together at 19. The links 18 are pivotally secured to the back of the door at a point 20, adjacent to 90

the meeting edges α of the doors, while the inner end of each of the links 17 is pivotally secured at 21 to an outstanding fixed bracket 22, secured usually to the wall of the building A.

The outer end of an actuating bar 23 is pivotally secured at 24 to each link 18, the point of attachment being intermediate the pivotal connections 19 and 20. The rear end of each actuating bar 23 is pivotally secured at 25 to a sliding plate D'. This plate D' is positioned adjacent to the plate D and is movably secured between the timbers C, C. Like the plate D, the plate D' is provided with laterally extending lugs 26 which travel in the guideways or grooves 15 of the timbers C, C. The two plates D and D' will normally travel in unison, and this may be accomplished by a locking mechanism, shown more fully in Figs. 3 and 4.

Depending from one of the plates, in this instance D', is a bell crank lever 28, pivotally mounted at 27. The lever has a hand hold 29 provided with an engaging jaw or pawl 30. On the under side of the other plate there is a shoulder or part 31 adapted for engagement with the pawl or jaw 30; as more clearly shown in Fig. 3. It will be manifest that when the two parts 30 and 31 are in engagement, as shown in Figs. 3 and 4, the plates D and D' will be securely locked together and that when motion is imparted to one plate, a corresponding movement of the other plate will occur.

In Fig. 2, the position of the pivoted links 17 and 18 and the operating links 23 are indicated in full lines, the doors B, B, being closed. When the doors B, B, are open, these links 17, 18 and 23 assume the positions indicated by the dotted lines. It will be noted that the links 17 are pivotally secured to the brackets 22 at a point substantially in line with the hinges b when extended at right angles to the plane of the door. When the doors are closed, the links 18 lie parallel with the doors and the links 17 stand at an angle to the doors. When the doors are open, the links 17 assume a position almost parallel to the plane of the door when closed, as shown by the dotted lines in Fig. 2, and the links 18 and 23 stand at an angle to the door, as also shown in dotted lines in said Fig. 2, their point of pivotal connection, 19, resting somewhat near the timbers C.

I have found that this arrangement and location of the link connections between the brackets 22 and the doors B, B, and their operative connection with the sliding plates D, D', affords a very strong and positive mechanism which responds readily when the motor is actuated, and one in which there is no dead center, whether the movement of the plates D, D', be in one direction or the other.

It may be desirable, at times, to separate the plates D and D', and to actuate one of the plates manually without the other, and in such event a simple pull on the hand hold 29 will disconnect the parts 30, 31, and permit of such movement.

In some instances, the hinged door may be jointed, one section of the door being hinged to fold upon the other section. In such event the toggle link 18 will not be connected to the swinging edge of the door as above described, but to the outer end of a bracket secured to that section of the door hinged to the building or fixed support A. This is shown in Fig. 5, where the hinged door B is provided with a foldable section B', hinged at b'. To the back of the door B, I attach a bracket arm E, to the outer end of which the pivot connection 20 for the toggle link 18 is located. The operation is obvious. In Fig. 6, I have shown another modification. It will be manifest that the movable element or plate D need not slide within or between the two timbers C and that any arrangement will answer whereby longitudinal movement is attained. In the arrangement illustrated in Fig. 6, the lugs and grooves are transposed, the lugs 16^a being on the beams C and the guide grooves 15^a being in the plate or movable element D.

Manifestly various other modifications may be made without departing from the principle of my invention of the toggle arrangement, a movable element, means for actuating the same and operative connections between the toggles and said movable element.

I claim as my invention:

1. Means for operating doors comprising in combination with a fixed support, a door hinged thereto and fixed guideways, a pair of plates movable in said guideways, toggle links operatively connecting one of said plates and the door, a motor for actuating one of said plates and means on one plate adapted for operatively engaging the other, whereby the two plates may move in unison, said means including a pivoted lever and pawl.

2. Door operating mechanism comprising a hinged door, a fixed guide, a movable element associated with the guide, an operating unit, having operative connections to actuate said movable element, a pair of toggle links, one pivotally connected to the door and the other pivotally connected to a fixed support, and an operating link pivotally connecting one of said toggle links with said movable element.

3. Door operating mechanism comprising a hinged door, a fixed guide positioned above the door normal to the plane of the door when the latter is closed, an element associated with the guide and movable longi-

tudinally with respect thereto, an operating unit operatively connected with said movable element, a pair of pivotally connected toggles or links, the free end of one being pivotally attached to the back of the door and that of the other similarly attached to a fixed support located back of the door, and a connecting link pivotally attached to the movable element and to that member of the 10 toggle which is attached to the door.

4. Means for operating doors comprising in combination with a fixed support and a door hinged thereto, of a guideway, a movable element, an operating link pivotally secured at one end to said plate, a pair of pivotally connected links, the free end of one of said links being pivotally connected to the fixed support at a point removed from but substantially in line with the door hinge 20 and the free end of the other link being pivotally connected to the back of the door near its non-hinged edge, a pivotal connection intermediate the ends of the last mentioned link, by which the operating link is connected thereto, an operating shaft, a crank on said shaft, a link connecting the crank with said element and means for rotating the shaft.

5. Means for operating doors comprising

in combination with a fixed support and a door hinged thereto, of a fixed guideway, 30 a movable element, an operating link pivotally secured at one end to said plate, a toggle comprising two links pivotally connected, the free end of one toggle link being pivotally connected to the fixed support at a point 35 removed from but substantially in line with the door hinge and the free end of the other toggle link being pivotally connected to the back of the door near its non-hinged edge, a pivotal connection intermediate the ends 40 of the last mentioned toggle link by which the operating link is connected thereto, an operating shaft, a crank on said shaft, a link connecting the crank with said movable 45 element and means including an electrically operated motor for actuating said movable element.

In testimony that I claim the foregoing as my invention I affix my signature, in the presence of two witnesses, this 8th day of 50 May, 1922.

HARRY G. AINSWORTH.
